CHARGE FORMING DEVICE

Wilford H. Teeter, Dayton, Ohio, assignor, by
mesne assignments, to Delco Products Corpora-
tion, Dayton, Ohio, a corporation of Dela-
ware

Application October 15, 1928, Serial No. 312,511
Renewed August 26, 1932

15 Claims. (Cl. 261—34)

This invention relates to a charge forming de-
vice for internal combustion engines and par-
ticularly to the type of charge forming device
which comprises a plurality of primary carbu-
retors, one for each intake port of the engine,
and which cooperate respectively with a plurality
of secondary mixing chambers located adjacent
the engine intake ports. These mixing chambers
are adapted to receive primary fuel mixture from
the primary carburetors and under certain oper-
ating conditions to receive additional air supplied
through the branches of an air manifold which
supplies air to all of said mixing chambers and
is provided with a single air inlet.

Examples of charge forming devices of this
character are disclosed in the copending applica-
tions of Wilford H. Teeter, Serial No. 221,372,
filed September 22, 1927, and Fred E. Aseltine,
Serial No. 286,975, filed June 20, 1928, which ma-
tured to Patent 1,819,526 granted August 18, 1931.

In devices of this character heretofore de-
signed, such as those disclosed in the above men-
tioned applications, various means are provided
for regulating the proportions of fuel and air in
the mixture under various operating conditions,
so as to provide the mixture necessary to most
satisfactorily operate the engine under all pos-
sible conditions of speed and load. These mixture
proportioning devices include means for enriching
the mixture to some extent on opening movements
of the throttle mechanism to provide the power
necessary during the accelerating period. Vari-
ous forms of fuel pumps have been provided to
supply additional fuel to enrich the mixture.
These pumps have been only partially satisfac-
tory for various reasons. For example, mechani-
cally operated pumps require numerous moving
parts which are subject to wear and also add to
the manufacturing difficulties. Also mechani-
cally operated pumps are not always effective to
supply the quantity of fuel desired, because of
the difficulty in maintaining the delivery con-
duits full of fuel and also because the pumps do
not always supply an amount of fuel proportional
to the increase of engine suction on any opening
movement of the throttle.

The present invention is in the nature of an
improvement on the devices disclosed in the above
applications and the primary object of the in-
vention is to provide means for supplying addi-
tional fuel to the mixture on opening movements
of the throttle which is simple in construction,
uniform in its operation under all conditions of
engine operation, and is effective to always supply
the desired amount of fuel. More specifically, it is

an object of the invention to provide a means for
supplying additional fuel during the accelerating
period which is operable always to supply an
amount of fuel proportional to the increase in
engine suction during said period.

According to the present invention these ob-
jects are accomplished by the provision of an
auxiliary fuel reservoir supplied with fuel from
the main fuel reservoir and communicating with
the cylinder of the air valve dash pot so that the
level of the fuel in said reservoir is raised and
lowered as the air valve is opened and closed.
A nozzle for supplying fuel to the mixture pas-
sage extends into the said reservoir but termi-
nates at a point normally above the level of the
fuel therein. In the form of the invention herein
illustrated, this nozzle extends to the secondary
air passage, but it is obvious that such nozzle
could supply fuel to the primary mixture passages
if desired. On opening movement of the air valve,
the fuel level in the reservoir is raised so that the
lower end of the nozzle is immersed and fuel is
immediately drawn into the secondary air passage
by the suction maintained therein at the delivery
end of the nozzle.

Further objects and advantages of the present
invention will be apparent from the following de-
scription, reference being had to the accompany-
ing drawing wherein a preferred embodiment of
one form of the present invention is clearly
shown.

In the drawing:

Fig. 1 is a vertical longitudinal section through
a charge forming device in which the present
invention is embodied.

Figs. 2 and 3 are sections on the lines 2—2 and
3—3 respectively of Fig. 1.

The device disclosed comprises a main air
manifold 10 having three outlet branches, the
middle branch 12 being shown herein. Each of
these branches communicates with one of the
intake ports 14 of a multi-cylinder engine. These
branches are each provided with an attaching
flange 16 for securing the manifold to the engine
block in the usual manner. Adjacent the inlet of
the manifold is provided a flange 18 to which the
main carburetor unit is adapted to be attached, as
shown in Fig. 1.

The carburetor unit comprises a main housing
20 having an attaching flange 22 adapted to be
secured to the flange 18 by screws 24. An air
inlet horn 28 is secured, in position to register
with an opening in the upper wall of the housing
20, in any suitable way. A casting 30, having
certain dash pot chambers and fuel passages

60

105

110

formed therein, is secured by screws to the lower wall of the housing 20 and a sheet metal fuel bowl 32 is held tight against an annular shoulder 34 on the housing by a screw 36 which is screwed into a portion of the casting 30, as shown in Fig. 1, or by any other suitable means. Fuel is conducted from a main source of supply to the fuel bowl through a conduit, not shown herein, and the flow of fuel is controlled by a float 38 operating in the usual manner to maintain a constant level of fuel in the bowl.

Fuel flows from the bowl 32 to a plurality of primary fuel nozzles 40, one of which is located in each of the primary mixture passages 42, the construction of which will be briefly described hereinafter. The fuel conduit between the fuel bowl and the nozzle comprises a vertical fuel passage 44, communicating at its upper end with a horizontal fuel canal 46, which connects with each of the nozzles 40 through orifices 48. Fuel is admitted to the passage 44 from the fuel bowl at low speeds through a fixed metering orifice 50 and at high speeds additional fuel is admitted through an orifice 52 controlled by a valve 54 in the manner set forth in the above mentioned applications. This valve passes through the hole in the top of the fuel bowl, which is of sufficient size to admit air to the top of the fuel bowl so as to maintain atmospheric pressure therein.

Fuel is lifted from the fuel bowl through the above described passage and nozzles 40 to the primary mixture passages by the suction therein. Closing movements of the throttle cause a reduction in this suction which might permit the fuel column to drop sufficiently to cause a temporary starving of the engine unless means were provided to prevent it. Such means comprise a check valve 56 provided in an enlarged chamber 58 at the junction of channels 44 and 46 and on reduction of the suction in the mixture passage, said valve seats on an annular rib 60 projecting above the bottom of the chamber 58 around the delivery end of the fuel passage 44, preventing downward flow of fuel through said passage.

Each primary fuel nozzle is provided with a main fuel outlet 62 in the top of the nozzle and a secondary fuel outlet comprising two orifices 64 and 66, in the vertical wall of said nozzle near the bottom of the primary mixing chamber. At relatively high speeds the mixing chamber suction is enough to lift fuel from the main outlet as well as from the orifices 64 and 66. At idling or low speed operation under load, however, the suction is sufficient to lift fuel only to some point between the top of the nozzle and the orifices 64 and 66, fuel flowing from these orifices by action of gravity. Each nozzle is provided with a restricted fuel metering orifice 68.

The primary mixture passages 42 are parallel to each other and close together as indicated in Fig. 2, and when the carburetor is attached to the manifold, these passages are in communication with conduits conveying the primary mixture to the secondary mixture chambers as fully disclosed in the copending applications above referred to. Adjacent the nozzles, the mixture passages are enlarged to form primary mixing chambers indicated at 43. A single throttle valve 70, which extends across all of the primary mixture passages controls the flow therethrough and is provided with grooves 72 which register with said passages. This throttle is operated by means fully described in the above copending applications, and which forms no part of the present invention. The middle primary mixture passage 42 communi-

cates with a tube 74, fixed in the manifold branch 12 and constituting one of the primary mixture conduits above referred to, which convey the primary mixture to the secondary mixing chambers, tube 74 being associated with the middle branch of the manifold and supplying primary mixture to the secondary mixing chamber formed therein.

Substantially all of the air entering the carburetor flows through the air horn 28 and is controlled by a main air valve 80, normally held against a seat 82 by a spring 84 received between the valve and a flange 86 projecting from a sleeve 88 slidably mounted on a stationary sleeve 90 fixed in the housing 20 and serving as a guide sleeve for the air valve stem 92 to which the air valve is secured.

When it is desired to choke the carburetor to facilitate starting of the engine, the flange 86 is adapted to be lifted, by means not shown herein, until the upper end of the sleeve 88 is moved into engagement with the valve to hold said valve against its seat. Sufficient air to carry the starting fuel from the nozzles to the intake ports of the engine is admitted through an elongated slot 94 formed in a plate 96 secured to the housing 20, as shown in Fig. 1.

The valve 80 admits air to a main air chamber 98 from which air flows to the primary mixture passage through the orifices 100 in the fuel and air chambers and to the secondary mixing chambers through a passage 102, which communicates with the inlet of the manifold 10. A manually operable throttle 104 operated simultaneously with the primary throttle 70 by means of operating connections, fully shown and described in the above mentioned applications, controls the passage of air through the passage 102.

On opening of either or both throttle valves, the suction on the air valve 80 is increased and the air valve is opened against the tension of its spring to admit additional air and increase the quantity of mixture supplied to the engine. The opening of the valve must be retarded to some extent to prevent addition of sufficient air to lean the mixture. A dash pot is provided to accomplish this result and also to prevent fluttering of the valve which comprises a cylinder 110 forming a part of the casting 30 and a piston 112 secured to the valve stem 92 by means of a flanged coupling 114, being clamped against said coupling member by a nut 116 threaded on the coupling member. A passage 118 hereinafter more fully described limits escape of fuel from the dash pot cylinder and determines the amount of resistance offered by the dash pot to any opening movement of the valve. The specific construction of the piston and cylinder is not material so far as the present invention is concerned and may be of any conventional design.

Communicating with the dash pot cylinder 110 by means of the passage 118, above mentioned, is an auxiliary fuel reservoir 120 which may be integral with the casting 30, as shown herein, or may be a separate member secured thereto. This reservoir is adapted to be filled with fuel from the main fuel reservoir by means of orifice 124 and is provided with a reduced extension 126 projecting upwardly from the main portion of the reservoir. The lower end of a fuel nozzle 128 projects into the upper end of said extension 126 and the upper end of said nozzle, as disclosed herein, terminates in the secondary air passage 102, and is adapted to supply fuel thereto during the accelerating period, as will be more

fully described hereinafter. The nozzle is provided with a restricted fuel metering outlet 129 at its upper end. The inner diameter of the extension 126 is of greater diameter than the outer diameter of the nozzle 128 so that a space 130 is provided between said nozzle and the wall of the reduced portion of the reservoir to permit the passage of air therethrough. Normally the lower end of the nozzle is above the fuel level maintained in said extension 126 so that the nozzle is ineffective to supply fuel to the secondary air passage except under certain operating conditions, air normally flowing through the space 130 and thence through the nozzle. However, on opening movements of the throttle to accelerate the engine, the level in the extension 126 is raised sufficiently to immerse the lower end of the nozzle, which will then immediately supply fuel to the secondary air passage. The dash pot piston 112 operates to lift the fuel level in the auxiliary reservoir as described. On opening movements of the air valve, the piston moves downwardly and forces fuel from the dash pot cylinder through the passage 118 raising the level of the fuel in the auxiliary reservoir to immerse the lower end of the nozzle 128 and fuel will then be drawn from the said nozzle by the suction in the secondary air passage, and since any excess fuel forced into the extension 126 by the dash pot piston merely runs out through space 130; there is no pumping of fuel through the nozzle and fuel flows therefrom at a rate proportional to the increase in suction in the secondary air passage.

The effective area of passage 118 may be adjusted by means of a valve 132 which is threaded on the casting 30 and is provided with a stuffing box 134 to prevent leakage of fuel around the valve. By variably positioning the valve 132, the resistance of the dash pot can be adjusted substantially as desired, but the valve should always be positioned so as to permit a flow of fuel through the passage 118 at least equal to the flow of fuel through the nozzle 128, otherwise the flow from the nozzle might stop before the opening of the throttle stopped because the fuel level in the extension 126 would be lowered below the lower end of the nozzle. Air would then flow through the nozzle until the fuel level were again raised.

The auxiliary fuel reservoir must have a capacity at least substantially equal to the amount of fuel displaced by the dash pot piston on maximum opening movement of the air valve. If the reservoir were of less capacity, any movement of the dash pot piston resulting in the displacement of a quantity of fuel greater than the capacity of the auxiliary reservoir would draw air into the dash pot cylinder on return movement of the piston.

It will be clear that the device constructed in accordance with this invention is always effective to supply an amount of fuel to the mixture passage on any opening of the throttle which is proportional to the increase in suction in said mixture passage, that said device is simple in construction, cheap and easy to manufacture, and has no moving parts whatever to become worn or get out of adjustment, is always uniform in its action and operative to enrich the mixture substantially simultaneously with any opening movement of the throttle.

While the form of embodiment of the present invention as herein disclosed, constitutes a preferred form, it is to be understood that other

forms might be adopted, all coming within the scope of the claims which follow.

What is claimed is as follows:

1. A charge forming device for internal combustion engines comprising a mixture passage, means for supplying fuel and air thereto, a throttle, a fuel reservoir, a fuel nozzle adapted to supply additional fuel to the mixture passage for acceleration and normally terminating above the fuel level in said reservoir, means in communication with said reservoir both above and below the fuel level therein and adapted to supply fuel to said nozzle, an air valve controlling admission of air to said mixture passage, a dash pot controlling the opening of said valve and comprising a cylinder supplied with fuel from said reservoir and a piston secured to the air valve and slidably in said cylinder, and means whereby said piston is effective to raise the fuel level adjacent the nozzle. 80

2. A charge forming device for internal combustion engines comprising a mixture passage, means for supplying fuel and air thereto, a throttle, a main fuel reservoir, a fuel nozzle adapted to supply additional fuel to the mixture passage 100 for acceleration and normally terminating above the fuel level in said reservoir, an air valve controlling admission of air to the mixture passage, a dash pot therefor comprising a piston secured to the valve and a cylinder in which the piston slides, an auxiliary fuel reservoir into which said nozzle projects, said auxiliary reservoir and cylinder being supplied with fuel from the main fuel reservoir and a passage connecting the cylinder and reservoir whereby movement of the piston 110 regulates the liquid level in said auxiliary reservoir, and means effecting communication between the upper part of said auxiliary reservoir above the normal level of the fuel therein and the upper part of said main fuel reservoir above 115 the fuel level therein.

3. A charge forming device for internal combustion engines comprising a mixture passage, means for supplying fuel and air thereto, a throttle, a main fuel reservoir, a fuel nozzle adapted 120 to supply additional fuel to the mixture passage for acceleration and normally terminating above the fuel level in said reservoir, an air valve controlling admission of air to the mixture passage, a dash pot therefor comprising a piston secured to the valve and a cylinder in which said piston slides having communication with the fuel reservoir, an auxiliary reservoir into which said nozzle projects and a passage connecting said auxiliary reservoir with the dash pot cylinder, said auxiliary reservoir having a capacity substantially 130 equal to the maximum volume of liquid displaced by the dash pot piston during opening of the air valve, and said auxiliary reservoir having communication with said main reservoir above the 135 fuel level therein.

4. A charge forming device for multicylinder engines comprising a plurality of secondary carburetors, a plurality of primary carburetors supplying fuel mixture thereto, means for supplying 140 fuel and air thereto, a secondary air passage supplying air to said secondary carburetors, a throttle, means for supplying additional fuel to said device to enrich the mixture for acceleration on opening movement of the throttle, flow of 145 fuel from said means being effected by the suction in the secondary air passage whereby the quantity of fuel supplied on any opening movement of the throttle is proportional to the increase in suction in the secondary air passage. 150

5. A charge forming device for multi-cylinder engines comprising a plurality of secondary carburetors, a plurality of primary carburetors supplying fuel mixture thereto, means for supplying fuel and air thereto, a secondary air passage supplying air to said secondary carburetors, a throttle, means for supplying additional fuel to said device to enrich the mixture for acceleration on opening movement of the throttle, said means comprising a single fuel nozzle communicating with the secondary air passage, the flow of fuel therefrom being controlled by the suction maintained adjacent said nozzle. 85

6. A charge forming device for internal combustion engines comprising a secondary mixing chamber, a primary mixture passage delivering a primary mixture of fuel and air to said secondary mixing chamber, means for supplying fuel and air to said primary mixture passage, a throttle, a secondary air passage supplying air to the secondary mixing chamber, a fuel reservoir, a fuel nozzle adapted to supply additional fuel to the secondary air passage to enrich the mixture for acceleration and normally terminating above the fuel level in said reservoir, means in communication with said reservoir both above and below the fuel level therein and adapted to supply fuel to said nozzle, and means operated by the suction in the secondary air passage on opening of the throttle to raise the fuel level adjacent the nozzle until said nozzle is immersed in the fuel. 90

7. A charge forming device for internal combustion engines comprising a secondary mixing chamber, a primary mixture passage delivering a primary mixture of fuel and air to said secondary mixing chamber, means for supplying fuel and air to said primary mixture passage, a throttle, a secondary air passage supplying air to the secondary mixing chamber, a fuel reservoir, a fuel nozzle adapted to supply additional fuel to the secondary air passage to enrich the mixture for acceleration and normally terminating above the fuel level in said reservoir, means in communication with said reservoir both above and below the fuel level therein and adapted to supply fuel to said nozzle, an air valve adapted to control admission of air to the secondary air passage and means operated by said air valve to raise the fuel level adjacent the nozzle until said nozzle is immersed in the fuel. 105

8. A charge forming device for internal combustion engines comprising a secondary mixing chamber, a primary mixture passage delivering a primary mixture of fuel and air to said secondary mixing chamber, means for supplying fuel and air to said primary mixture passage, a throttle, a secondary air passage supplying air to the secondary mixing chamber, a main fuel reservoir, a fuel nozzle adapted to supply additional fuel to the secondary air passage to enrich the mixture for acceleration and normally terminating above the fuel level in said reservoir, an auxiliary reservoir adapted to supply fuel to said nozzle normally ineffective, and means operated by the suction in the secondary air passage to raise the level of fuel in said auxiliary reservoir to render the nozzle effective, and means effecting communication between the upper part of said auxiliary reservoir above the normal level of the fuel therein and the upper part of said main reservoir above the fuel level therein. 110

9. A charge forming device for internal combustion engines comprising a secondary mixing

chamber, a primary mixture passage delivering a primary mixture of fuel and air to said secondary mixing chamber, means for supplying fuel and air to said primary mixture passage, a throttle, a secondary air passage supplying air to the secondary mixing chamber, a fuel reservoir, a fuel nozzle adapted to supply additional fuel to the secondary air passage to enrich the mixture for acceleration and normally terminating above the fuel level in said reservoir, means in communication with said reservoir both above and below the fuel level therein and adapted to supply fuel to said nozzle, an air valve controlling admission of air to said secondary air passage, a dashpot controlling the opening of said air valve comprising a cylinder supplied with fuel from said reservoir and a piston secured to the air valve and slideable in said cylinder, and means whereby said piston is effective to raise the fuel level adjacent the nozzle. 115

10. A charge forming device for internal combustion engines comprising a primary mixture passage, means for supplying fuel and air thereto, a secondary mixing chamber into which said primary mixture passage delivers a primary mixture of fuel and air, a main fuel reservoir, a secondary air passage for supplying air to said secondary mixing chamber, an air valve controlling admission of air to said secondary air passage, a dashpot for said valve comprising a relatively movable piston and cylinder, a fuel nozzle communicating with the secondary air passage to supply fuel thereto during the acceleration period, an auxiliary fuel reservoir into which said nozzle projects and which is ineffective to supply fuel to said nozzle under normal operating conditions, a passage connecting the dashpot cylinder and auxiliary reservoir whereby opening of the valve regulates the fuel level in the auxiliary reservoir, and means effecting communication between said auxiliary reservoir above the level of the opening of said nozzle and the upper part of said main reservoir above the fuel level therein. 120

11. A charge forming device for internal combustion engines comprising a mixture passage, means for supplying fuel and air thereto, a throttle, a main fuel reservoir, a submergeable fuel nozzle adapted to supply additional fuel to the mixture passage for acceleration and normally terminating above the fuel level in said reservoir, an air valve controlling admission of air to the mixture passage, a dash pot therefor comprising a piston secured to the valve and a cylinder in which the piston slides, an auxiliary fuel reservoir into which said nozzle projects, an opening in the reservoir adjacent the nozzle to permit overflow of surplus fuel when the nozzle is submerged, said auxiliary reservoir and cylinder being supplied with fuel from the main fuel reservoir and a passage connecting the cylinder and reservoir whereby movement of the piston regulates the liquid level in said auxiliary reservoir. 125

12. A charge forming device for internal combustion engines comprising a mixture passage, means for supplying fuel and air thereto, a throttle, a main fuel reservoir, a submergeable fuel nozzle adapted to supply additional fuel to the mixture passage for acceleration and normally terminating above the fuel level in said reservoir, an air valve controlling admission of air to the mixture passage, an auxiliary fuel reservoir into which the nozzle projects and in which the fuel level is normally maintained at a level below the lower end of said nozzle, an opening in the reser-

voir adjacent the nozzles to permit overflow of surplus fuel when the nozzle is submerged, means for supplying fuel to the auxiliary reservoir from the main reservoir, and means operated by the 5 air valve for raising the level of fuel in said auxiliary reservoir following any opening movement of the throttle to submerge the end of said nozzle.

13. A charge forming device for internal combustion engines comprising a secondary mixing chamber, a primary mixture passage delivering a primary mixture of fuel and air to said secondary mixing chamber, means for supplying fuel and air to said primary mixture passage, a 10 throttle, a secondary air passage supplying air to the secondary mixing chamber, a fuel reservoir, a fuel nozzle adapted to supply additional fuel to the secondary air passage to enrich the mixture for acceleration and normally terminating 15 above the fuel level in said reservoir, and means operated by the suction in the secondary air passage on opening of the throttle to raise the fuel level adjacent the nozzle until said nozzle is immersed in the fuel.

14. A charge forming device for internal combustion engines comprising a secondary mixing chamber, a primary mixture passage delivering a primary mixture of fuel and air to said secondary mixing chamber, means for supplying fuel 20 and air to said primary mixture passage, a throttle, a secondary air passage supplying air to the secondary mixing chamber, a fuel reservoir, a main fuel nozzle adapted to supply additional fuel to the secondary air passage to enrich the mixture for acceleration and normally terminating above the fuel level in said reservoir, an auxiliary reservoir adapted to supply fuel to said nozzle normally ineffective, and means operated by the 25 suction in the secondary air passage to raise the level of fuel in said auxiliary reservoir to render the nozzle effective.

30

and air to said primary mixture passage, a throttle, a secondary air passage supplying air to the secondary mixing chamber, a fuel reservoir, a fuel nozzle adapted to supply additional fuel to the secondary air passage to enrich the mixture for acceleration and normally terminating above the fuel level in said reservoir, an air valve adapted to control admission of air to the secondary air passage and means operated by said air valve to raise the fuel level adjacent the nozzle until said nozzle is immersed in the fuel.

15. A charge forming device for internal combustion engines comprising a secondary mixing chamber, a primary mixture passage delivering a primary mixture of fuel and air to said secondary mixing chamber, means for supplying fuel and air to said primary mixture passage, a throttle, a secondary air passage supplying air to the secondary mixing chamber, a fuel reservoir, a main fuel nozzle adapted to supply additional fuel to the secondary air passage to enrich the mixture for acceleration and normally terminating above the fuel level in said reservoir, an auxiliary reservoir adapted to supply fuel to said nozzle normally ineffective, and means operated by the suction in the secondary air passage to raise the level of fuel in said auxiliary reservoir to render the nozzle effective.
